(57) **CLAIM**

The ornamental design for an LED tile, as shown and described.

DESCRIPTION

FIG. 1 is a rear perspective view of an LED tile;

FIG. 2 is a front view thereof;

FIG. 3 is a rear view thereof;

FIG. 4 is a side view thereof;

FIG. 5 is a second side view thereof;

FIG. 6 is a top view thereof; and,

FIG. 7 is bottom view thereof.

The dash-dash-dash broken lines in the Figures are for the purpose of illustrating unclaimed portions of the LED tile and form no part of the claimed design.

The dash-dot-dash boundary lines define boundaries of the claimed design and forms no part of the claimed design.

The shade lines in the Figures show contour and not surface ornamentation.

1 Claim, 7 Drawing Sheets
